RECTAL MEDICATOR

Louis A. Pierson, Meriden, Conn.

Application March 2, 1953, Serial No. 339,548

5 Claims. (Cl. 128—261)

1

This invention relates to a rectal medicator and has for an object to provide an improved rectal medicator so as to provide a means for rectal medication in place of rectal suppositories.

A further object of this invention is to provide a rectal medicator that will provide for escape of flatus without contaminating the medicine being inserted, which may be so manipulated that the flatus, often present and usually disturbed by the insertion of the rectal medicator, may be first expelled, and then the medicine may be dispensed into the rectum.

A further object of this invention is to provide a rectal medicator that may be used for inserting liquid medicine into the rectum and yet keep it free of contamination from flatus while it is inserted, which may be manipulated to expel any flatus present in the rectum before the medicine is inserted.

Still a further object of this invention is to provide an improved rectal medicator for inserting liquid medicine into the rectum in a measured amount by providing a collapsible container of a dosage size so that it can be inserted into the rectum by squeezing the container with pressure along the length of the thumb.

Briefly, this improved rectal medicator provides a container for a dosage of rectal medicine, a medicator tube on the container, and a rectum penetrating tube threaded onto the medicator tube, the rectum penetrating tube having an enlarged end limiting the insertion of the tube into the rectum, and a dispensing opening at the penetrating end of the tube, and a flatus escape opening in its enlarged end. Before inserting the rectum tube, the medicator and rectum tubes are so manipulated that there is a passage open through the rectum tube from the penetrating end to the enlarged end, which permits the flatus to escape without contaminating the medicine. After the flatus has escaped, the tubes are manipulated to provide a continuous passage from the medicine container through both tubes to within the rectum, then the container is squeezed to dispense the medicine within the rectum as desired.

With the foregoing and other objects in view, this invention comprises the combination, construction and arrangement of parts hereinafter set forth, claimed and disclosed in the accompanying drawings, wherein:

Fig. 1 is an elevational view of the improved rectal medicator of this invention.

Fig. 2 is a view similar to Fig. 1, but partly in section.

2

Fig. 3 is an exploded, partly sectional view, on a much larger scale:

Fig. 4 is a fragmentary sectional view, of the medicator in flatus expelling position.

Fig. 5 is a similar view in medicine dispensing position.

There is shown at 10 the rectal medicator of this invention. This rectal medicator 10 includes a small diametered cylindrical rectum penetrating tube 11, preferably of substantially uniform diameter from its rectum penetrating end 12 to its opposite end 14 where it forms a juncture with its large hollow threaded end 15, this threaded end 15 being of so substantial a size that it will not readily enter the rectum as does the tube 11, but instead, provides a stop limiting the insertion of the tube 11. Intermediate the juncture 14 and the threaded end 15 there are provided at least one or more side openings 16 therethrough, the openings 16 being so located as to remain outside of the rectum when the tube 11 has been inserted. A dispensing side opening 17 is located adjacent the rectum penetrating end 12 of the tube 11.

A medicator tube 20 is also provided with a large threaded end 21 having external threads 22 to cooperate with the threads 23 of the rectum tube threaded end 15, and the medicator tube 20 has an open end 24 through which the medicine passes when it is being dispensed.

The diameter of the medicator tube 20 is about that of the diameter of the rectum tube rectum penetrating end 11, and the length of the medicator tube 20 is such, in relation to the large bore portion end 15 of the rectum tube 11 that manipulation of the threaded ends of the tubes 11 and 20 may cause the open end 24 of the tube 20 to be spaced from the juncture 14 within the tube 11 and its end 15, as shown in Figs. 2 and 4, or may cause the open end 24 to seat within the juncture 14 and thus provide a continuous passageway through the tube 20 and the tube 11.

Attached to the medicator tube 20, as by internal threads 25 thereon cooperating with external threads 26 is a medicine container 27. This container 27 is a collapsible tube, preferably of polyethylene plastic because of its elastic properties, but obviously may be of any suitable material. Both tubes 11 and 20 will also be of suitable material, possibly the same as the container. As shown, the container 27 is about two and one half inches long, elliptical, tapering and about the width of the average thumb, just the size to hold a single dosage of medicine, so that the medicine can be squeezed out by pressure 55 along the length of the thumb.

The container 27 may be reused or thrown away, or the rectum tube may be saved for reuse, depending on the cost of cleaning and sterilizing as compared to the cost of the original article.

In operation, this rectal medicator is intended to take the place of rectum suppositories, and while particularly intended for liquid medicines, may likewise be used with paste medicines. Before the rectum tube 11 is inserted, the medicator tube 20 is manipulated to the position shown in Fig. 2 and Fig. 4, with the open end 24 of tube 20 spaced from the juncture 14. Inasmuch as this will not be externally visible, the medicator tube thread 22 may be first threaded into rectum tube thread 23 as far as it will go, which of course will seat the open end 24 of medicator tube 20 against juncture 14, as shown in Fig. 5. Then, the thread 22 is backed out one turn, separating the end of the medicator tube from the juncture 14 as shown in Figs. 2 and 4. Then, the rectum tube is inserted with the parts in this position. Any flatus within the rectum, disturbed by the insertion of the tube 11, will pass through dispensing opening 17 into the tube 11 and then out side openings 16 to the atmosphere without contaminating the medicine in the container 27. After all the flatus has been expelled, the container 27 is rotated the one turn necessary to move the medicator tube 20 into seating position against juncture 14 as shown in Fig. 5 to provide a continuous passage from the container 27 through medicator tube 20 and rectum tube 11 to the dispensing opening 17. Then, the thumb is squeezed along the length of the container 27 to thus dispense the medicine from container 27 through both tubes 20 and 11 and the side opening 17 against the wall of the rectum, thus avoiding head-on-pressure, and providing immediate contact of the medicine with the wall of the rectum for absorption of the medicine.

While the device has been shown and the structure described in detail, it is obvious that this invention is not to be considered as being limited to the exact form disclosed, and that changes in detail and construction may be made therein within the scope of what is claimed, without departing from the spirit of this invention.

Having thus set forth and disclosed the nature of this invention, what is claimed is:

1. A rectal flatus releasing medicator comprising a hollow rectum tube having a large portion and a small diameter cylindrical end portion, the small end portion of said tube being of a diameter to readily penetrate a rectum, the large portion of said tube being of a diameter too large to readily penetrate the rectum, said small end portion having an opening located remotely from its juncture with the large portion, said large portion having at least one flatus releasing side opening, a medicator tube having an axial opening at one end of a size to form a passage to said rectum penetrating small end portion, the other end of said medicator tube being externally complementary to and mounted in the interior of the end of the large portion of said rectum tube, said rectum tube being manipulatable over said medicator tube until the open end of said medicator tube abuts the juncture end of said rectum penetrating tube portion and thus forms a continuous passageway from said medicator tube to said rectum penetrating tube opening, said rectum tube being adjustable to break said continuous passageway and permit flatus entering said rectum penetrating opening

to bypass said medicator tube and escape through said flatus releasing side opening in said rectum tube large portion, and means on said medicator for attaching a medicine dispensing means to said medicator for use when said medicator tube and said rectum penetrating tube are in continuous passageway position to dispense medicine from the dispensing means through said continuous passageway into the rectum.

2. A rectal flatus releasing medicator comprising a hollow rectum tube having a large portion and a small diameter cylindrical end portion, the small end portion of said tube being of an external diameter to readily penetrate a rectum, the large portion of said tube being of an external diameter too large to readily penetrate the rectum, said small end portion having a dispensing opening located remotely from its juncture with the large portion, said large portion having at least one flatus releasing side opening, the end of said large portion remote from its juncture with the small portion being internally cylindrical, a medicator tube having an axial opening at one end of a size to form a passage to said rectum penetrating small end portion, the other end of said medicator tube being externally cylindrical complementary to and mounted in the internally cylindrical large end of said rectum tube, said rectum tube being manipulatable over said medicator tube until the open end of said medicator tube abuts the juncture end of said rectum penetrating tube and thus forms a continuous passageway from said medicator tube to said rectum penetrating tube opening, said rectum tube being adjustable to break said continuous passageway and permit flatus entering said rectum penetrating opening to bypass said medicator tube and escape through said flatus releasing side opening in said rectum tube large portion, and means on said medicator for attaching a medicine dispensing means thereto for dispensing medicine therefrom and through said medicator tube and through said rectum tube into the rectum when in continuous passageway position.

3. A rectal flatus releasing medicator comprising a hollow rectum tube, having a large portion and a small diameter cylindrical end portion, the small end portion of said tube being of an external diameter to readily penetrate a rectum, the large portion of said tube being of an external diameter too large to readily penetrate the rectum, said small end portion having a side medicine dispensing opening located remotely from its juncture with the large portion, said large portion having at least one flatus releasing side opening, the end of said large portion remote from its juncture with the small portion being internally cylindrical, a medicator tube having an axial opening at one end of a size to form a passage to said rectum penetrating small end portion, the other end of said medicator tube being externally cylindrical complementary to and mounted in the internally cylindrical large end of said rectum tube, said rectum tube being manipulatable over said medicator tube until the open end of said medicator tube abuts the juncture end of said rectum penetrating tube and thus forms a continuous passageway from said medicator tube to said rectum penetrating tube opening, said rectum tube being adjustable to break said continuous passageway and permit flatus entering said rectum penetrating opening to bypass said medicator tube and escape through said flatus releasing side opening in said rectum tube

large portion, and means on said medicator for attaching a medicine dispensing means thereto for dispensing medicine therefrom through said medicator tube and through said rectum tube into the rectum when in continuous passageway position, said medicine dispensing means comprising a medicine dose containing collapsible tube secured to said medicator.

4. A rectal flatus releasing medicator comprising a hollow rectum tube, having a large portion and a small diametered cylindrical end portion, the small end portion of said tube being of an external diameter to readily penetrate a rectum, the large portion of said tube being of an external diameter too large to readily penetrate the rectum, said small end portion having a medicine dispensing opening located remotely from its juncture with the large portion, said large portion having at least one flatus releasing side opening, the end of said large portion remote from its juncture with the small portion being internally threaded, a medicator tube having an axial opening at one end of a size to form a passage to said rectum penetrating small end portion, the other end of said medicator tube being externally threaded complementary to and threaded within the internally threaded large end of said rectum tube, said rectum tube being threadable over said medicator tube until the open end of said medicator tube abuts the juncture end of said rectum penetrating tube and thus forms a continuous passageway from said medicator tube to said rectum penetrating tube opening, said rectum tube being partially unthreadable to break said continuous passageway and permit flatus entering said rectum penetrating end opening to bypass said medicator tube and escape through said flatus releasing side opening in said rectum tube large portion, and means on said medicator for attaching medicine dispensing means thereto for dispensing medicine therefrom through said medicator tube and through said rectum tube into the rectum when in continuous passageway position

5. A rectal flatus releasing medicator compris- 45

ing a hollow rectum tube, having a large portion and a small diametered cylindrical end portion, the small end portion of said tube being of an externally substantially uniform diameter to readily penetrate a rectum, the large portion of said tube being of an external diameter too large to readily penetrate the rectum, said small end portion having a side medicine dispensing opening located remotely from its juncture with the large portion, said large portion having at least one flatus releasing side opening, the end of said large portion remote from its juncture with the small portion being internally threaded, a medicator tube having an axial opening at one end of a size to form a passage of said rectum penetrating small end portion, the other end of said medicator tube being externally threaded complementary to and threaded within the internally threaded large end of said rectum tube, said rectum tube being threadable over said medicator tube until the open end of said medicator tube abuts the juncture end of said rectum penetrating tube and thus forms a continuous passageway from said medicator tube to said rectum penetrating tube opening, said rectum tube being partially unthreadable to break said continuous passageway and permit flatus entering said rectum penetrating end opening to bypass said medicator tube and escape through said flatus releasing side opening in said rectum tube large portion, and internal thread means on said medicator tube for attaching medicine dispensing means thereto for dispensing medicine therefrom through said medicator tube and through said rectum tube into the rectum when in continuous passageway position, said medicine dispensing means comprising a medicine dose containing collapsible externally threaded tube internally threaded to said medicator tube.
